UNITED STATES PATENT OFFICE.

GERTRUDE R. BONEBRIGHT, OF GRAND RAPIDS, MICHIGAN.

GARMENT-SUPPORTER.

1,344,856.

Specification of Letters Patent. Patented June 29, 1920.

Application filed May 15, 1919. Serial No. 297,317.

To all whom it may concern:

Be it known that I, GERTRUDE R. BONEBRIGHT, a citizen of the United States, residing at 624 Loraine Bldg., Grand Rapids, 5 county of Kent, State of Michigan, have invented certain new and useful Improvements in Garment-Supporters, of which the following is a specification.

This invention relates to improvements in 10 garment supporters.

The objects of this invention are to provide a garment supporter for infants' use which will serve as an effective diaper and stocking support and at the same time allow 15 the child complete freedom of movement.

I accomplish the objects of my invention by the devices and means described in the following specification. The invention is 20 clearly defined and pointed out in the claim. A structure which is a preferred embodiment of my invention is fully illustrated in the single perspective view in the accompanying drawing.

25 Shoulder straps 1—1 are provided having elastic ends 1'—1' connected to front and rear diaper attaching straps 2 and 3. These straps are provided with safety pins 4 or other devices for attaching them to the infant's diaper. A back strap 5 connects the shoulder straps 1—1 across the back and a little below the shoulder at about the waist line and a front cross strap 6 keeps the shoulder straps in place at the front. These 30 cross straps are preferably elastic to prevent injury to the spine and delicate organs in the pelvic cavity. A side strap 7, one at each side, is secured at the connection of the front and back straps 5 and 6 to the 35 shoulder straps 1—1 and forms a loop down at each side of the person of the wearer. To this loop is secured a runner ring 9 to which is connected and carried thereby an elastic strap 8 with garment supporter fasteners 40 10—10 on the usual bifurcated strap type at the bottom.

In use this structure gives the child com-

plete freedom of movement without any binding of the person. The shoulder straps are held properly in place by the front and back straps and the elastic connections to the diaper supporting straps hold the diaper securely in place and permits free and easy movement of the wearer. The stockings are held up by the stocking supporters which 50 play readily back and forth upon the supporting loop 7 and do not cause any strain upon the person except on the shoulders when standing, the pull being evenly distributed between the back and front of the 55 shoulder straps at each side.

While I have shown the structure using the elastic straps, the elastic straps might be omitted and a very satisfactory structure produced. The style of diaper supporting 60 fastener whether of the safety pin or other style, and the style of hose supporter clasp are immaterial to the invention.

Having thus described my invention I wish to claim the same specifically in the 70 form that I have it and also generally as indicated in the appended claim.

Having thus described my invention, what I claim as new and desire to secure by Letters Patent is:

In a garment supporter, the combination of shoulder straps obliquely and centrally extended to a diaper supporting strap at front and back, cross straps at front and back to keep the shoulder straps in proper 80 spaced relation, a loop strap with central depending portion at each side, the opposite ends of which are secured to the shoulder straps, and a stocking supporter on a suitable runner on each of said depending portions, coacting substantially as described for 85 the purpose specified.

In witness whereof I have hereunto set my hand and seal in the presence of two witnesses.

GERTRUDE BONEBRIGHT. [L. s.]
